UNITED STATES PATENT OFFICE.

B. FRANK MOHR, OF MIFFLINBURG, PENNSYLVANIA.

STEAM-BOILER.

SPECIFICATION forming part of Letters Patent No. 309,484, dated December 16, 1884.

Application filed April 5, 1884. (No model.)

To all whom it may concern.

Be it known that I, B. FRANK MOHR, a citizen of the United States, and a resident of Mifflinburg, in the county of Union and State 5 of Pennsylvania, have invented certain new and useful Improvements in Steam-Boilers; and I do hereby declare that the following is a full, clear, and exact description of the invention, which will enable others skilled in 10 the art to which it appertains to make and use the same, reference being had to the accompanying drawings, which form a part of this specification, and in which—

Figure 1 is a vertical sectional view of my 15 improved steam boiler or generator. Fig. 2 is a horizontal sectional view taken on the line *x x* in Fig. 1, and Fig. 3 is a horizontal sectional view taken on the line *y y* in Fig. 1.

The same letters refer to the same parts in 20 all the figures.

This invention relates to boilers for steam-engines; and it has for its object to provide a device which shall possess superior advantages in point of simplicity, durability, and 25 general efficiency.

To this end it consists in certain improvements in the construction of the same, which will be hereinafter fully described, and particularly pointed out in the claim.

30 A in the drawings designates the fire-box, which may be made of wrought-iron, in a cylindrical shape, substantially as shown, and provided at the bottom with the grate B. C is the crown-sheet, from whence the flues D D 35 extend upwardly, they being inclosed by a vertical cylindrical casing, E, having at its upper end a top sheet, F, in which the upper ends of the flues D are fixed. The furnace or fire-box A is inclosed by a sheathing, G, con-

nected to the bottom of the said fire-box by an 40 annular ring, H, of steel or wrought-iron, to which the said fire-box and sheathing are riveted or otherwise suitably connected. The sheathing G is connected in like manner by an annular ring, I, with the lower end of the 45 casing E, above which it extends, and is provided with a detachable top or cover, J. Smoke-stacks K K extend from diametrically- 50 opposite sides of the casing G, a short distance above the ring I.

The operation of this invention will be readily understood from the foregoing description, taken in connection with the drawings hereto annexed. There is a direct upward draft through the flues, thence down around the water-space, and finally out through the smoke- 55 stacks. The latter, being located on opposite sides of the boiler, will equalize the draft and render it steady and even. By removing the top of the boiler the flues may be easily and 60 conveniently cleaned.

I claim as my invention and desire to secure by Letters Patent of the United States—

As an improvement in steam boilers or generators, the herein-described device, comprising the fire-box A, crown-sheet C, sheathing G, connecting-rings H I, casing E, top sheet, F, flues D, detachable cover J, and the smoke-flues K K, all arranged and operating substantially as and for the purpose herein shown and 65 specified.

In testimony that I claim the foregoing as my own I have hereunto affixed my signature in presence of two witnesses.

B. FRANK MOHR.
